DESIGN FOR A DOOR-KNOB.

SPECIFICATION forming part of Design No. 12,550, dated November 1, 1881.
Application filed September 24, 1881. Term of patent 7 years.

UNITED STATES PATENT OFFICE.

RODOLPHE CHRISTESEN, OF NEW BRITAIN, CONNECTICUT, ASSIGNOR TO
THE RUSSELL & ERWIN MANUFACTURING COMPANY, OF SAME PLACE.

DESIGN FOR A DOOR-KNOB.

SPECIFICATION forming part of Design No. 12,550, dated November 1, 1881.
Application filed September 24, 1881. Term of patent 7 years.

To all whom it may concern:

Be it known that I, RODOLPHE CHRISTESEN, of New Britain, in the county of Hartford and State of Connecticut, have invented a new and useful Design for Door-Knobs; and I do hereby declare that the following specification, taken in connection with the accompanying illustration, forming a part of the same, is a full, clear, and exact description thereof.

My novel design relates to the contour and ornamentation of the face of a door-knob; and it consists in a knob having its face concaved or recessed below a surrounding rim and provided with a flower superimposed upon said recessed surface.

As shown in the illustration, the face A is

concave or recessed below the surrounding rim
a. Centrally located upon the recessed face is a flower, B, in relief.

The flower shown in the illustration is a daisy; but other flowers may be substituted without changing the characteristic feature of the design.

What I claim, and desire to secure by Letters Patent, is—

The design for a door-knob, substantially as shown and herein described.

RODOLPHE CHRISTESEN.
